UNITED STATES PATENT OFFICE.

HENRY G. VOIGHT, OF NEW BRITAIN, CONNECTICUT.

CHECK FOR SLIDING DOORS.

1,069,079.

Specification of Letters Patent. Patented July 29, 1913.

Application filed January 18, 1913. Serial No. 742,805.

To all whom it may concern:

Be it known that I, HENRY G. VOIGHT, a citizen of the United States, residing at New Britain, county of Hartford, State of Connecticut, have invented certain new and useful Improvements in Checks for Sliding Doors, of which the following is a full, clear, and exact description.

This invention relates to a safety check or 10 blocking device for sliding doors and more particularly used in connection with such doors when employed for elevator shafts.

The present invention provides a simple 15 yet effective checking device which will yieldingly resist the attempted reopening of such a door during its closing movement, thus deterring persons outside of the elevator shaft from forcing the door open while the same is in the act of closing, such preventive measures being particularly necessary when the door is closing and the elevator has started away from the landing before the door has been fully closed.

The improved check device forming the 20 subject matter of the present invention is arranged to offer a resistance (which may be predetermined) to such opening of the door, but is adapted to yield to pressure greater than such predetermined resistance, so that 25 the door may be forced open under such conditions. Such opening pressure must perforce be comparatively great, but not so great as to be beyond attainment by an adult, such as the elevator operator.

Such a device as described will enable the 30 operator to leave his car at a landing with the well-door partially closed, but not latched from the interior. The door will be safe against ordinary opening effort on the 35 part of an unauthorized person, but is, nevertheless subject to opening through the efforts of the operator.

These and other advantages will be more 40 clearly apparent from the detailed description following, taken in connection with the accompanying drawings thereof, and illustrating a preferable embodiment of the invention.

In these drawings: Figure 1 is a fragmentary view of the top edge of a door and casing with my invention applied thereto, the door being shown in closed position. Fig. 2 is a similar view showing the door partially closed and the parts of the checking device in a position to offer a yielding 50 resistance to reopening movement. Fig. 3

is a fragmentary vertical section on the line 3—3 of Fig. 1. Fig. 4 is a fragmentary view in elevation of the top of a door and casing with the checking parts in their forced position. Fig. 5 is a detail view in elevation and on an enlarged scale, of the pawl member of the checking device.

Referring to the drawings by numerals, 1 indicates a sliding door and 2 its casing. 60 The door 1 is provided with suitable opening and closing mechanism. Any suitable means may also be provided to hold the door locked in closed position. The door 1 is mounted in any suitable manner to slide, as, 65 for example, by supporting the same from an overhead track 3 by means of a hanger 4. The check device which coöperates with this door comprises a pawl 5 having a slot 6 therein by means of which it is loosely pivoted on a headed pivot stud 7 carried by the bracket plate 8 which may be mounted at a suitable position as, on the overhead track 3.

9 indicates a rail in the form of a rack bar provided with suitable teeth 10 facing rearwardly and adapted to coöperate with the tail of the loosely pivoted pawl 5. The forward edge of the rack bar 9 terminates at or near the forward edge of the sliding door 1, and the rear end of said rack bar terminates 75 at a point forward of the pivoted pawl 5 as suggested in Fig. 1 of the drawings. At a point above the head of the pawl 5 and preferably in line with its pivot stud 7, is located a tubular housing 11 which may be 80 provided with suitable securing flanges 12 by means of which it may be secured to the bracket plate 8 or overhead track 3, or to any other suitably positioned support. The upper end of this tubular housing is 85 integrally threaded. A centrally apertured plug 13 screws into this upper threaded end of the housing, the aperture in this plug being

of slightly greater diameter than the upper 90 end of a checking plunger 14. This plunger 100 is provided intermediate its ends with a collar 15 and at its lower end with an abutment head 16. The plunger is inserted within the housing from its lower open end, a coiled spring 17 of substantial strength being inserted on the plunger between the collar 15 thereof, and the nut 13, closing the upper end of the tubular housing. After the plunger has been inserted within its housing, the lower end of the housing is closed 105 by means of a washer 18 which may be rigidly fastened to said housing by suitable 110

means, and forms an abutment for the collar 15 and serves to limit the downward movement of the plunger. It will be evident that the coiled spring 17 will engage the collar 15 5 to move the plunger downwardly and bring its collar 15 against the abutment washer 18. The parts are so proportioned that in this normal position of the plunger, its head 16 will lie closely adjacent the head of the pawl 10 5 when the latter is in its lowermost or dropped position, such as shown in Figs. 1, 3 and 5 of the drawings. It will also be evident that the plug 13 may be operated by suitable means, to increase or decrease the 15 pressure of the coiled spring, and thereby vary the amount of pressure which is required to move the plunger 14 upwardly against the force of said spring.

The operation of the parts is as follows. 20 Assuming that the door is fully closed and in the position shown in Fig. 1 of the drawings, the operating mechanism of the door is actuated to move the door in open direction. When this is done, the rear end of the 25 rack bar 9 will engage the depending pawl 5 and swing it upwardly and backwardly, so that the rack bar 9 will travel freely over said pawl on its opening movement. This pawl 5 is so located that when the door is 30 fully opened or at least opened beyond a point determined by the position of the forward end of the rack bar, the forward edge of this rack bar will clear the pawl and allow it to again assume a depending position 35 9 as indicated in Figs. 1 and 5. When the door is moved from this open position toward closing position, the forward end of the rack bar 9 will engage the pawl 5 and swing it upwardly and forwardly in the direction suggested in Fig. 2, whereupon its 40 tail will drop back of the locking shoulders formed by the teeth 10—10 as the same successively pass under the pawl. Any attempt to reopen the door, therefore, while the door 45 is moving toward closed position and the pawl is resting upon the rack bar 9 and against one of its teeth, will result in the pawl moving upwardly relatively to its pivot stud until its head engages the abutment 50 head 16 of the checking plunger and further movement of the pawl is resisted by the power of the coiled spring 17. This spring in practice will be very stiff and powerful, so that it will take extraordinary pressure 55 against the door to move the pawl upwardly relative to its pivot to thereby move the checking plunger 14 upwardly in its housing and against the pressure of the coiled spring, such action being suggested by Figs. 2 and 4 of the 60 drawings. Upon the application of such extraordinary pressure, the pawl will be moved from the position shown in Fig. 2 to that shown in Fig. 4 and further pressure will swing said pawl rearwardly and permit the 65 door being opened, the pawl, after being

forced by the initially engaged tooth, dropping down on its pivot stud and permitting the rack bar 9 to pass freely thereover.

From the foregoing, it will be evident that I have provided in connection with a 70 sliding door having suitable mechanism for opening and closing the same, means which yieldingly resist an attempted reopening of the door after the latter has passed a predetermined point in its closing movement, 75 the invention being arranged to permit free movement of the door when open beyond the predetermined point of yielding resistance.

While I have described and shown the 80 checking mechanism carried at the upper edge of the door, it will be evident that the action would be just as effective if the pawl 5 were carried at the lower edge of the door and the rack bar 9 attached to the sill.

While I have herein described a specific 85 embodiment of the invention, it will be understood, of course, that the same is susceptible of structural modification within the spirit of the invention and the scope of the 90 appended claims.

What I claim, therefore, and desire to secure by Letters Patent is:

1. In a door controlling device, a door, mechanism for opening and closing said door, and means for yieldingly resisting an 95 opening movement of the door when the door passes a predetermined point in its closing movement, said means being arranged to permit the free movement of said door when open beyond said predetermined 100 point.

2. In a door controlling device, a door, mechanism for opening and closing said door, and means for yieldingly resisting an opening movement of the door when the 105 same has been partially closed beyond a predetermined point in its closing movement, said means being arranged to permit the free movement of the door when open beyond said predetermined point and when 110 closed beyond a predetermined point.

3. In a door controlling device, a movable door, mechanism for opening and closing said door, a locking device yieldingly resisting an opening movement of said door 115 when the same passes beyond a predetermined point in its closing movement and comprising two parts freely movable past each other during door closing movement but adapted to engage on a reverse movement of the door, one of said parts being arranged to yield relative to the other under pressure. 120

4. In a door controlling device, a movable door, mechanism for opening and closing said door, a locking device yieldingly resisting an opening movement of said door when the same passes beyond a predetermined point in its closing movement and comprising two parts freely movable past 130

each other during door closing movement but adapted to engage on a reverse movement of the door, one of said parts being arranged to yield relative to the other under 5 pressure, and means for regulating the degree of pressure under which said part may yield.

5. In a door controlling device, a movable door, mechanism for opening and closing 10 said door, a locking device yieldingly resisting an opening movement of said door when the same passes beyond a predetermined point in its closing movement and comprising a bodily movable pawl and a co- 15 operating rack mounted to be freely movable past each other during closing movement of said door, but adapted to engage on a reverse movement of the door, and spring means yieldingly holding said pawl 20 in engagement with said rack.

6. A stop for sliding doors comprising a bodily movable depending stop element, a rail, the length of said rail being less than the full range of the sliding movement of 25 said door, one of said parts being carried by the door and the other by a relatively stationary member and said stop being mounted at a point to the rear of said rail

when the door is fully closed, said point being also forward of the rail when said 30 door is opened beyond a predetermined point, and means coöperating therewith to cause said stop to yieldingly resist reopening of the door on its closing movement while said stop is resting on said rail.

7. A stop for sliding doors comprising a depending loosely pivoted pawl, a coöperating rack, the length of said rack being less than the full range of the sliding movement 40 of the door, one of said parts being carried by the door and the other by a relatively stationary member, and said pawl being pivoted at a point to the rear of said rack when the door is closed beyond a predetermined point, said pawl being also forward of the rack when the door is opened beyond a predetermined point, and spring 45 checking means coöperating with said pawl to hold it in engagement with said rack to yieldingly resist re-opening of the door on 50 its closing movement while said pawl is resting on said rack.
